CAMERA CARRYING CASE

Vincent F. Lang, Rochester, N.Y., assignor to Eastman
Kodak Company, Rochester, N.Y., a corporation of
New Jersey

Filed Nov. 29, 1963, Ser. No. 77,622

Term of patent 14 years

(Cl. D87—5)

FIG.1

FIG.7

FIG. 8

FIG. 9

FIG. 10

FIG. 1 is a front elevational view of a camera carrying case, in a closed condition, showing my new design;

FIG. 2 is a top plan view thereof;

FIG. 3 is a rear elevational view thereof;

FIG. 4 is a bottom plan view thereof;

FIG. 5 is an elevational view of the right end thereof;

FIG. 6 is an elevational view of the left end thereof;

FIG. 7 is a perspective view of the same in an open condition;

FIG. 8 is a rear elevational view thereof, showing a modified form wherein the beading on certain of the edges is omitted and wherein the top edge of the left end wall is notched out rather than being provided with an elongated slot;

FIG. 9 is an elevational view of the left end of the FIG. 8 embodiment; and

FIG. 10 is a perspective view of the FIG. 8 embodiment in an open condition.

I claim:

The ornamental design of a camera carrying case, as shown and described.
